MODIFIED TRIPLETS WITH REDUCED SECONDARY SPECTRUM

CROSS REFERENCE TO RELATED APPLICATIONS

Reference is made to commonly assigned and copending U.S. patent applications; Ser. No. 185,496, entitled Lens With Reduced Secondary Spectrum, filed Oct. 1, 1971, in the name of W. H. Price; Ser. No. 185,602, entitled Printer Lens, filed Oct. 1, 1971, in the name of W. H. Vangraafeiland.

BACKGROUND OF THE INVENTION

1. Field of the Invention

This invention relates to lenses and in particular to modified triplets with reduced secondary spectrum which may be used in printers.

2. Description of the Prior Art

Secondary spectrum is the inability of a lens, even when corrected for longitudinal chromatic aberration, to focus all wavelengths of light at the same point. In a design which improves only the monochromatic aberration corrections of an achromatized lens, secondary spectrum becomes the limiting aberration of the lens. In monochromatic prints, secondary spectrum tends to reduce the contrast of the final print, particularly in fine detail areas. In color prints, secondary spectrum is manifested as a spreading of color from dark areas into adjacent light areas, a phenomenon known as color fringing or halo.

It has been known to use modified triplets of the type having two outer positive components surrounding a middle negative component for photographic printing lenses. Many such lenses are well corrected for monochromatic and longitudinal chromatic aberration. Secondary spectrum is limited in such triplets by careful selection of the materials used in each element of the triplet. Examples of such materials may be found in U.S. Pat. Nos. 2,645,154 and 2,645,156.

SUMMARY OF THE INVENTION

An object of the present invention is to provide a printer lens having substantially improved secondary spectrum correction.

It is another object of the present invention to provide such a printer lens with improved secondary spectrum correction which also is well corrected for other aberrations such as axial or oblique spherical aberration, coma, field curvature or astigmatism.

These and other objects are accomplished according to this invention by lenses constructed according to the parameters to be set forth more fully in the detailed description of the preferred embodiments presented below.

BRIEF DESCRIPTION OF THE DRAWING

In the detailed description of the preferred embodiments of the invention presented below, reference is made to the accompanying drawing which is a diagrammatic axial cross-section of a printer lens according to this invention.

DESCRIPTION OF THE PREFERRED EMBODIMENT

For all purposes of describing or claiming of the invention herein, the term lens shall be used to describe the complete lens and not elements or components thereof. The long conjugate side of the lens is considered the front. In all of the following examples, the lens components are numbered from front to rear with Roman numerals; the lens elements are numbered from front to rear with Arabic numerals. The indexes of refraction N for the D line of the spectrum, the Abbe numbers V, the radii of curvature R, the thicknesses T and the separations S are numbered by subscript from front to rear. Radii of curvature having centers of curvature to the rear of the surface are considered positive; those with centers of curvature to the front of the surface are considered negative. All parameters are based upon a lens focal length of 100mm.

In all embodiments of the invention, as illustrated in FIG. 1, component I is a positive doublet consisting of a front positive biconvex element 1 and a rear negative biconcave element 2. Component II consists of a negative biconcave element 3. Component III is a rear positive biconvex doublet consisting of a front meniscus negative element 4 concave to the rear and a rear positive biconvex element 5.

Printer lenses which are well corrected for secondary spectrum may be made according to this invention by following the specifications in the examples presented below.

EXAMPLE 1

Element	f/4.5		Radius mm	Mag.=12.000 x Thickness or Separation mm
	N _D	V _D		
35	1	1.62005	63.5	R ₁ = 35.170
	2	1.51700	64.5	R ₂ =-32.836
	3	1.65317	39.7	R ₃ =220.47
	4	1.65317	39.7	R ₄ =-44.142
	5	1.74500	46.4	R ₅ = 33.670

EXAMPLE 2

Element	f/7.09		Radius mm	Mag.=7.250 x Thickness or Separation mm
	N _D	V _D		
55	1	1.62005	63.5	R ₁ = 32.352
	2	1.51700	64.5	R ₂ =-36.418
	3	1.65317	39.7	R ₃ =107.20
	4	1.65317	39.7	R ₄ =-42.253
	5	1.74500	46.4	R ₅ = 32.096

3
EXAMPLE 3

Element	N_D	V_D	$F=100\text{mm}$	Mag. = $12,000 \times$ Thickness or Separation mm
			Radius mm	
1	1.62005	63.5	$R_1 = 36.544$	$T_1 = 14.461$
2	1.51700	64.5	$R_2 = -32.632$	$T_2 = 2.699$
3	1.65317	39.7	$R_3 = 314.64$	$S_1 = 2.120$
4	1.65317	39.7	$R_4 = -42.913$	$T_3 = 3.144$
5	1.74500	46.4	$R_5 = 34.025$	$S_2 = 3.689$
			$R_6 = 351.12$	$T_4 = 2.304$
			$R_7 = 24.732$	$T_5 = 7.083$
			$R_8 = -44.503$	

Examples 1-3 are similar to each other in optical performance and differ only in the selection of design parameters but each is well corrected for secondary spectrum.

The invention has been described in detail with particular reference to preferred embodiments thereof, but it will be understood that variations and modifications can be affected within the spirit and scope of the invention.

I claim:

1. A printer lens having a middle negative component surrounded by two positive doublets, said lens being constructed according to the following table:

Element	N_D	V_D	Radius mm	Thickness or Separation mm
1	1.62005	63.5	$R_1 = 35.170$	$T_1 = 13.784$
2	1.51700	64.5	$R_2 = -32.836$	$T_2 = 2.667$
3	1.65317	39.7	$R_3 = 220.47$	$S_1 = 2.056$
4	1.65317	39.7	$R_4 = -44.142$	$T_3 = 2.074$
5	1.74500	46.4	$R_5 = 33.670$	$S_2 = 3.035$
			$R_6 = 314.75$	$T_4 = 4.840$
			$R_7 = 26.483$	$T_5 = 6.870$
			$R_8 = -45.368$	

wherein, from front to rear, the lens elements are numbered from 1-5, the corresponding indexes of refraction and Abbe numbers are for the D line of the spectrum, the radii are numbered from R_1 to R_8 , the thicknesses are numbered from T_1 to T_5 and the air

spaces are numbered from S_1 to S_2 .

2. A printer lens having a middle negative component surrounded by two positive doublets, said lens being constructed according to the following table:

Element	N_D	V_D	Radius mm	Thickness or Separation mm
10	1	1.62005	63.5	$R_1 = 32.352$
	2	1.51700	64.5	$R_2 = -36.418$
15	3	1.65317	39.7	$R_3 = 107.20$
	4	1.65317	39.7	$R_4 = -42.253$
	5	1.74500	46.4	$R_5 = 32.096$
				$R_6 = 218.36$
				$R_7 = 23.861$
				$R_8 = -42.009$

20

wherein, from front to rear, the lens elements are numbered from 1-5, the corresponding indexes of refraction and Abbe numbers are for the D line of the spectrum, the radii are numbered from R_1 to R_8 , the thicknesses are numbered from T_1 to T_5 and the air spaces are numbered from S_1 to S_3 .

3. A printer lens having a middle negative component surrounded by two doublets, said lens being constructed according to the following table:

Element	N_D	V_D	Radius mm	Thickness or Separation mm
35	1	1.62005	63.5	$R_1 = 36.544$
	2	1.51700	64.5	$R_2 = -32.632$
40	3	1.65317	39.7	$R_3 = 314.64$
	4	1.65317	39.7	$R_4 = -42.913$
45	5	1.74500	46.4	$R_5 = 34.025$
				$R_6 = 3.144$
				$R_7 = 3.689$
				$R_8 = -44.503$

wherein, from front to rear, the lens elements are numbered from 1-5, the corresponding indexes of refraction and Abbe numbers are for the D line of the spectrum, the radii are numbered from R_1 to R_8 , the thicknesses are numbered from T_1 to T_5 and the air spaces are numbered from S_1 to S_2 .

UNITED STATES PATENT OFFICE
CERTIFICATE OF CORRECTION

Patent No. 3,692,386

Dated

September 19, 1972

Inventor(s) C. J. Melech

It is certified that error appears in the above-identified patent
and that said Letters Patent are hereby corrected as shown below:

Column 2, Example 1   Please delete "1.6537" and substitute
Element 4   therefor --1.65317--

Column 4, line 27   Please delete "S₃" and substitute there-
                                  for --S₂--

Column 4, line 41   Please delete "T₃=3.144" from the "Radius
mm" column and insert --T₃=3.144-- in the
"Thickness or Separation mm" column

Signed and sealed this 17th day of April 1973.
